Fred B. Wiseman, Denver, Colo.

Application December 27, 1937, Serial No. 181,758

5 Claims. (Cl. 312—173)

This invention relates to portable cabinets and carrying-cases adapted for the storage and convenient transportation of a plurality of articles, such as tools, and has as an object to provide an improved cabinet arranged to facilitate access to and orderly storage of the articles housed therein.

A further object of the invention is to provide an improved portable cabinet wherein a plurality of independently-swingable leaves are arranged for the support of articles housed within said cabinet and disposed for cooperation with each other and with other elements of said cabinet to complete the cabinet enclosure.

15 A further object of the invention is to provide an improved portable cabinet that is simple and inexpensive of manufacture, susceptible of practical embodiment in a variety of specific forms and arrangements, adapted for the storage and transportation of a multiplicity of articles in readily accessible position and relation, and which is highly practical, convenient, and efficient in use.

20 My invention consists in the construction, arrangement, and combination of elements herein-after set forth, pointed out in my claims, and illustrated by the accompanying drawing, in which—

Figure 1 is an isometric view of one simple and convenient construction of a cabinet embodying the principles of the instant invention, wherein said cabinet is shown in assembled, closed position ready for practical use. Figure 2 is a horizontal section taken transversely of the 25 showing of Figure 1, broken lines indicating alternative positions of certain elements of the construction. Figure 3 is a vertical section taken on substantially the indicated line 3—3 of Figure 2 and illustrating certain modifications of construction not shown in the latter figure. Figure 4 is a horizontal section taken transversely of a modified construction and arrangement of elements constituting a portable cabinet. Figure 5 is a fragmentary, detail section on an enlarged scale, illustrating the cooperation of adjacent movable elements in effecting closure of the cabinet assembly. Figure 6 is a view similar to Figure 5 and illustrating a modified arrangement of the cooperating adjacent movable elements. Figure 7 is a fragmentary, detail view, partly in section, illustrating rolling support means advantageously associated with the movable elements of the cabinet assembly. Figure 8 is a fragmentary, detail view of the upper margins of movable elements of the assembly and

illustrating an arrangement designed to prevent the hooking of one of said elements over the forward margin of an adjacent element.

The improved cabinet comprises, essentially, top and bottom members suitably and rigidly interconnected in spaced, parallel relation, a side wall member fixedly connecting between said top and bottom members, and a plurality of independently-swingable leaves hinged to said fixed side wall member and constructed and arranged to cooperate with the top and bottom members, and with each other, to complete a cabinet enclosure wherein the spaced leaves define storage compartments adapted to house articles suitably supported on and carried by said leaves. In the construction illustrated by Figures 1, 2 and 3, the cabinet frame is shown as comprising a rectangular bottom member 10, a corresponding rectangular top member 11 spaced in vertical registration with and above the member 10, a back 10 wall 12 fixedly connecting between corresponding margins of and in perpendicular relation with the members 10 and 11, and a suitable brace 13 fixedly engaging and extending between the margins of the members 10 and 11 opposite to those 15 engaged with the back plate 12. The cabinet frame resulting from the cooperative association of the elements 10, 11, 12 and 13 is a rigid unit 20 open on three sides and maintained in the relationship desired by means of the fixed engagement of the back wall 12 and brace 13 with the top and bottom members. To close the sides of the cabinet frame adjacent the back member 12, panels 14 of a size to fill the area defined by adjacent margins of the members 10, 11 and 12, 25 are hinged, as indicated at 15, to outer margins of the back member 12 and are thus disposed to swing relative to said member into and out of 30 closing cooperation with the top and bottom members of the assembly. Intermediate the 35 panels 14, a plurality of leaves 16 are disposed perpendicularly between the top and bottom members 11 and 10 and are spaced apart along the back member 12 in such number and specific 40 spacing as may be expedient or desirable in a given construction, each of the leaves 16 being hinged, as indicated at 17, to said back member 12 to swing freely and in substantially filling 45 relation between the frame members 10 and 11 about an axis fixed relative to the back member 12. The forward margins of the panels 14 and leaves 16 terminate adjacent the plane defined by the forward edges of the frame members 10 and 11 and are provided with angularly-related flanges or heads 18 disposed to margin- 50 55

ally abut in coplanar relation when the panels 14 and leaves 16 are swung to perpendicular relation with the back member 12, and thereby close the front area of the cabinet frame, the 5 panels 14 functioning to close side portions of said frame when in the relation specified. Co-operating ears 19 may be formed on the top member 11 and panels 14 in position to register when said panels are in closing relation with 10 the cabinet frame and thereby provide means for latching the assembly in its closed position, pins or locks of suitable type being readily engageable with the registered ears to prevent their separation and thus preclude opening of the cabinet 15 until the latching means has been released, immobilizing of the panels 14 in closing relation with the cabinet frame acting to fix the leaves 16 in coplanar alignment of their head elements 18 as a frontal closure for the cabinet assembly. A 20 suitable handle 20 may be fixed to the top member 11 for convenience in lifting, carrying, and transporting the cabinet and its contents.

The panels 14 and leaves 16 provided with head elements 18 in a given or initial construction 25 of the assembly suffice to close and complete such assembly, though it may be that the number of leaves 16 is inadequate to the contemplated use of the assembly and that the spacing between adjacent leaves 16, or between the 30 panels 14 and the adjacent leaves 16, is in excess of that required for the contemplated use of the assembly and could be advantageously employed for additional storage. To adapt the construction for adjustment of its storage capacity, additional hinge elements 17' are 35 preferably provided on the back member 12 intermediate the hinge elements 17 and between the hinge mountings 15 and 17, which elements 17' are disposed and arranged for cooperation with 40 complementary elements carried by one margin of a supplementary leaf 16' which may thereby be mounted to swing in the same manner as the leaves 16 between said headed leaves or between a panel 14 and the adjacent leaf 16. The supplementary leaves 16' do not carry the head or 45 flange elements 18 and are of a size to terminate just within the elements 18 carried by the leaves 16. The supplementary leaves 16' may be added to or removed from the original assembly as desired, and may be used in such numbers and 50 combinations with the original assembly as may best adapt the latter to a particular use or function.

Since the leaves 16 swing about separate axes, 55 there is a tendency for one margin of a head element 18 to hook within or without and hence overlap on the adjacent margin of the head element carried by an adjacent leaf 16, thus making it difficult to properly align said head elements as a front closure for the assembly. This 60 difficulty may be conveniently obviated by the construction shown in Figure 8, wherein guide flanges 18' are provided on and in fixed relation with top margins of the leaves 16 and panels 14 65 and in perpendicular relation with said leaves and panels immediately below the top member 11 of the assembly, said guide flanges 18' preferably being marginally coincident with the head elements 18 and tapering from their junction with said head elements rearwardly and 70 toward the hinged margins of the leaves and panels. Since the guide flanges 18' are disposed in a common plane perpendicular to the hinge axes of the leaves and panels, margins of said 75 guide flanges will engage with like margins of

adjacent flanges, or be engaged by the upper corners of the head elements 18 and thus prevent the overlapping of one head element 18 on any portion of an adjacent head element.

In the construction according to Figure 4, the 5 elements of the invention are essentially the same as hereabove described, and differ from those shown in Figure 1 in form and specific details of arrangement, only. The modified construction contemplates the use of arcuate top 10 and bottom members having the form of incomplete circular discs 21, which discs are interconnected in the desired spaced relation by means of a fixed post 22 engaging between their centers and functionally and structurally replacing the back member 12 of the first disclosure. The side panels 14 and intermediate leaves 16 are hinged to and grouped about the post 22 and extend radially therefrom to support arcuate head and flange members 18'' disposed 15 for edge engagement to define a cylindrical outer wall for the assembly, the segment omitted from the members 21 providing a space wherein the panels 14 may swing toward each other to permit separation of the head and flange element 18'' 20 for access to the compartments defined between the panels 14 and leaves 16, as is clearly shown by broken lines in Figure 4. The modified construction just described may include the latching ears 19 and a plurality of brace members 13, not 25 shown in Figure 4, to function for the purpose and in the relationship specified for said elements hereabove, as well as the auxiliary hinge elements 17', the supplementary leaves 16', and the guide flanges 18' as previously described in 30 connection with the rectangular embodiment of the invention.

As is clearly shown in Figure 3, the inner surfaces of the panels 14 and both surfaces of the leaves 16 and 16' are adapted to receive and support the articles to be stored and transported in the cabinet. Suitable brackets, hooks, clips, and like conventional supporting means may be disposed on and about the supporting surfaces specified in any arrangement suitable to position 40 and group articles within the cabinet for convenience of use and facility of access, a plurality of conventional tool elements being shown in Figure 3 in a convenient grouping on a portion of one of the leaves 16. In addition, trays 23 50 may be horizontally disposed in fixed relation on and for extension perpendicularly from the surfaces of the leaves 16 and 16' and panels 14, in such number and specific arrangement as may be advantageous or desirable, which trays are 55 convenient for the reception, storage, and transportation of articles, tools, and accessories too small in size or otherwise not adapted for independent support against the vertical surfaces.

The improved cabinet may be formed of any 60 suitable material in any specific manner adapted to the construction described, and the hinge mounting of the panels 14 and leaves 16 and 16' may be varied in its specific construction to best fit the materials and fabricating methods employed in a given instance. To facilitate marginal registration and coplanar alignment of the flange and head elements 18 and 18'', adjacent margins of said elements are preferably formed to meet on curved areas rather than along plane 70 margins, one of said edges being concaved for reception of and cooperation with a convex adjacent edge, as is clearly shown in Figures 5 and 6; the construction of Figure 5 relating to a relatively-thick-walled arrangement, such as 75

would result from the use of wood or like material, while the showing of Figure 6 relates more directly to sheet metal or like thin-walled construction.

5 In relatively large embodiments, or where the leaves 16 and 16' are heavily loaded, it may be expedient to provide a rolling bearing between the forward lower corners of said leaves and the bottom member 10 to relieve the hinge connection 10 of strain, in which event an arrangement such as is shown in Figure 7, and comprising a spring-backed ball element 24 recessed within the lower margin of a leaf 16 in position to bear against and roll on a track element 25 carried by or 15 recessed within the bottom member 10, may be associated in equivalent form with one or all of said leaves 16.

20 Since the invention is susceptible of practical embodiment in a variety of forms and specific arrangements, and since variations and modifications in the construction, form and arrangement of the elements shown and described may be had without departing from the spirit or principle of the invention, I wish to be understood as being limited solely by the scope of the appended 25 claims, rather than by any details of the illustrative showing and foregoing description.

I claim as my invention—

30 1. A cabinet comprising a rigid frame including spaced top and bottom members in fixed relation with an interconnecting back member, swingable panels hinged to margins of said back member and arranged to close side portions of said frame at times, a plurality of swingable 35 leaves independently hinged to said back member in spaced relation intermediate said panels, and flanges on the free margins of said panels and leaves adapted to cooperate in abutting relation to form a front closure for said frame when 40 said panels are disposed in closing relation with the frame side portions.

2. A cabinet comprising spaced top and bottom members in fixed relation with an interconnecting back member, panel elements hinged to opposite margins of said back member and swingable into and out of closing relation with side portions of the assembly, a plurality of leaf elements 45 independently hinged to said back member in spaced relation intermediate said panels, and flanges on the free margins of said panel and leaf elements arranged for coplanar, marginal interengagement to form a frontal closure for 50

the assembly when said panel elements are in closing relation with the side portions thereof.

3. A cabinet comprising spaced top and bottom members in fixed, perpendicular relation with an interconnecting member, swingable panels hinged to said interconnecting member between and in perpendicular relation with said top and bottom members and disposed to form side closures for the assembly at times, a plurality of swingable leaves independently hinged to said interconnecting member in spaced relation perpendicular 10 between said top and bottom members, and flange elements on the free margins of said panel and leaf elements disposed for cooperation through marginal interengagement to complete 15 the enclosure of said assembly when said panel elements are in side-closing relation therewith.

4. In a cabinet having spaced top and bottom members in fixed relation with an interconnecting member, article supporting and carrying means arranged to facilitate access to articles housed within the cabinet and cooperable to complete the cabinet enclosure, said means comprising panel elements hinged to said interconnecting member in perpendicular relation between 20 said top and bottom members and swingable into and out of side closing relation with the assembly, a plurality of leaf elements independently hinged to said interconnecting member in spaced relation perpendicularly between 25 said top and bottom members, and flange elements on the free margins of said panel and leaf elements disposed for marginal interengagement to complete the assembly enclosure when 30 said panel elements are in side-closing relation 35 therewith

5. A cabinet comprising a rigid frame including spaced top and bottom members in fixed relation with an interconnecting back member, swingable panels hinged to margins of said back member and arranged to close side portions of said frame at times, a plurality of swingable leaves independently hinged to said back member in spaced relation intermediate said panels, flanges on the free margins of said panels and leaves adapted to cooperate in abutting relation 40 to form a front closure for said frame when 45 said panels are disposed in closing relation with the frame side portions, and supplementary leaves removably and replaceably hinged to said back member between adjacent flanged leaf and panel members. 50

FRED B. WISEMAN.
